UNITED STATES PATENT OFFICE.

GEORG SPIESS, OF LEIPZIG-REUDNITZ, GERMANY.

PAMPHLET-COVERER.

1,116,946.

Specification of Letters Patent. Patented Nov. 10, 1914.

Application filed March 21, 1914. Serial No. 826,451.

To all whom it may concern:

Be it known that I, GEORG SPIESS, a subject of the Emperor of Germany, residing in Leipzig-Reudnitz, Germany, have invented 5 certain new and useful Improvements in Pamphlet-Coverers, of which the following is a specification.

It is important for the successful operation of pamphlet covering machines that 10 the individual sheets which go to make up a pile, be presented to the glue coated cover in such manner that each and every sheet will be uniformly brought in contact therewith so as to be securely glued thereto. 15 Now according to this invention it is proposed to attain this object by the provision at the end of the sheet feed conveyer of oscillating members which are journaled so as to be brought by oscillating movement alternately into the plane of the path of the 20 sheet piles and to be erected vertically or approximately so if desired. The parts of a machine of this kind necessary for the understanding of this invention are illustrated 25 by way of example in the accompanying drawings, in which:

Figure 1 is an elevation, Fig. 2 a lateral view of the machine, and Fig. 3 is a lateral view of the delivery device of the same.

30 The individual sheet piles A are fed forward by a conveyer B at certain predetermined or definite intervals. According to this invention plates or arms C are flexibly arranged at the end of this conveyer B so 35 as to be capable of being lowered between the conveyer bands and thereby to be brought into the path or track of the sheet piles. As soon as a pile A arrives above these plates C the latter are tripped up into 40 the vertical position indicated in dotted lines whereby the pile is caused to drop vertically on to a cover D which previously has had its back coated with glue and has been placed on a supporting table E', E². The 45 plates C are caused to oscillate about their pivots by means of an eccentric C' which is coupled through the links C''' and C' to the shaft upon which they are carried. In this action the freely dropping sheets of the 50 pile A are individually seated on the glued back of the cover thereby insuring a sound connection with the glued part. In their movement the dropping paper piles are guided between vertical walls F and G. For 55 the completion of the pamphlet, roller pairs may in a known manner be used by which

the paper pile together with the glued-on cover is carried down and finally the cover is caused to be pressed against the paper pile. To this end, in the example shown, the 60 rollers H and J are arranged above the table E', E², the roller H being movable toward the roller J. This may be effected with the aid of a bell crank lever K actuated by a connecting rod L which by means 65 of a roller N is guided on a cam disk M arranged on the driving shaft. By means of these rollers the paper pile A after being seated on the cover D is caused to move downward with the cover folded thereon. 70 Beneath the passage in the table are arranged further roller pairs O, P and Q, R, of which O and Q are relatively movable with regard to the stationary rollers P and R respectively, similar to the rollers H and 75 J. Now the arrangement is such that the rollers H, O and Q are consecutively given a lateral displacement and that only those rollers are always operative which for the time being are to act on the pamphlet. The 80 movement of the rollers O and Q is effected by similar means, namely, by bell crank levers K', K² with the aid of connecting rods L', L² driven by cam disks M', M² respectively, which latter are mounted on the 85 same driving shaft that carries the cam M. In this way the descending pamphlet is first compressed between the rollers O, P and as it advances between the bands S, T, it is brought between the rollers Q and R by 90 which it is delivered to a support U. At this point the individual covered paper piles or pamphlets are finally compressed between a movable plate or jaw V and a stationary counter-plate or abutment V'. 95

In the case of heavy and thick paper piles and weak or thin covers, there is a danger that the dropping paper piles pull down the covering D before the rollers H and J have approached one another. To counteract this, a movable plate or obturator W is arranged below the passage in the table. This plate may, for instance, be carried in guides on one of the table leaves E' so that it may be advanced in order to cover the passage between these table parts. In this case the paper piles in dropping on to the back of the cover D press the latter against the plate W at the same time themselves assuming an upright position whereby the back of each 110 sheet is reliably brought into contact with a glued part of the back of the cover. The

surfaces of the plate W may be roughened, corrugated or ribbed to cause the glue on the back of the cover more intimately to penetrate the individual backs or back edges of the sheets. After thus bringing the paper piles against the plate W, the latter is withdrawn, for instance, by means of a cam actuating a connecting rod L³, the end of which is attached to the plate W by a lever X so that the passage in the table is opened.

At the point at which the descending paper pile is brought to rest, that is to say, at the point U a presser band Y guided over rollers Z is so arranged as to travel in the direction of the back of the cover and thereby to exert a presser action on the back longitudinally in order again to force the glue to penetrate between the adjacent edges of the individual sheets. Moreover, this stroking arrangement insures a uniform distribution of the glue at the connecting points and the band Y used for this purpose may consist of rubber or other elastic material.

What I claim and desire to secure by Letters Patent is:—

1. A pamphlet covering machine comprising in combination a sheet pile conveyer, a supporting table upon which a glued pamphlet cover is carried, an oscillating plate adapted to remove the sheet pile from said conveyer and direct it onto the said cover, means for withdrawing said cover and sheet pile together from said table in such manner that the cover is firmly pressed around the sheet pile while being withdrawn, substantially as described.

2. A pamphlet covering machine comprising in combination a sheet pile conveyer, a

supporting table upon which a glued pamphlet cover is carried, vertical guide plates above said table, an oscillating plate adapted to deliver a sheet pile from said conveyer to said guide plates, means arranged below said table adapted to receive said sheet pile with the cover folded thereon and to exert pressure upon them as they are moved vertically downward, a support upon which said pamphlets are delivered and a presser band beneath said support, substantially as described.

3. A pamphlet covering machine comprising in combination a sheet pile conveyer, a supporting table adapted to carry a glued cover back, an oscillating member adapted to be alternately brought into the path of the sheet pile conveyer and to be moved so as to direct the sheet pile in a downward direction into contact with said glued cover, pairs of rollers arranged in super-position and adapted to successively exert pressure on the downwardly moving covered sheet pile, means for laterally displacing one movable roller of each pair during the descent of the sheet pile, means at the delivery point of the sheet piles adapted finally to press a plurality of sheet piles and a pressing band below said means adapted to exert a pressure along each sheet pile subsequent to its delivery from the said pressure rollers, substantially as described.

In testimony whereof I have affixed my signature in presence of two witnesses.

GEORG SPIESS.
